FURRIER'S KNIFE

Edward A. Schmidt, Ridgewood, N. Y.

Application July 7, 1937, Serial No. 152,343

2 Claims. (Cl. 30—331)

This invention relates to furriers' knives, and particularly to the type wherein a pair of separable plates are utilized as holders and for the retention of interchangeable blades that are replaceable after wear.

The principal object of the invention is to provide a reliable, efficiently operable, efficiently utilizable, and improved furrier's knife.

Another object is to provide a furrier's knife of the above type with reliable, efficient, and improved means for locking together its holding plates, for the secure, safe, and proper retention of the cutting blade during utilization of the implement.

15 Other objects and advantages will hereinafter appear.

In the accompanying drawing,—

Fig. 1 is a general elevation showing the furrier's knife of this invention, as it appears during insertion or replacement of the cutting blade thereof.

Fig. 2 is an elevation showing the knife as it appears when in condition for utilization.

Figs. 3, 4 are transverse-section end elevations, in an enlarged scale, of the knife, as it appears in Fig. 2 on the lines 3—3 and 4—4 respectively of Fig. 2.

Fig. 5 is a plan view of the knife shown in Fig. 2.

30 Fig. 6 is a plan view showing a detail of the invention.

Fig. 7 is an elevation of a modification of the invention.

Fig. 8 is a transverse-sectional end elevation 35 of the furrier's knife shown in Fig. 7, the view being in an enlarged scale on the line 8—8 of Fig. 7.

Fig. 9 is a plan view showing a detail of the modification.

40 The furrier's knife 1 comprises a pair of plates 2, 3, that are similarly configurated in the manner shown, the former constituting the front plate and the latter the rear plate, and both plates are pivotally hinged to each other at

45 4, whereby they may be separated from each other in scissor-like manner as shown in Fig. 1 and brought together into registry with each other as illustrated in Fig. 2. A razor-like cutting blade 5 is insertible into the holder plates 2, 3, by means of apertures 6 thereof slipping mountably over registering pins 7 projecting from the plate 3, and holes 8 formed in the plate 2 fitting over the terminals of the said pins, as shown in Figs. 3, 4, the plates 2, 3 being provided with registering gaps 9 for effectively

working with the blade 5. Upon the interior side 10 of the front plate 2 is pivotally secured at 11 an arm 12 for locking the plates 2, 3 to each other for retention of the blade 5 after it has been mounted in the knife, said arm being made of a single piece of integral metal comprising a large wing 13 which is located between the plates 2, 3, a clamp portion 14 for engaging the plate 2, and a clamp portion 15 for engaging the plate 3.

When it is required to remove and replace the blade 5, the locking arm 12 is swung upwardly from its locking or operative state shown in Fig. 2 to the raised or inoperative position shown in Fig. 1. The holder plates 2, 3 may be then separated to the displaced position shown in Fig. 1, and the blade 5 may be removed and another replaced, whereupon the plate 2 may be reengaged with the pins 7 and the locking arm swung downwardly for clamping the plates 2, 3 to each other with the portions 14, 15, to securely retain the cutting blade 5 in requisite operative condition within the knife. When the knife and locking arm 12 are thus both in operative state, the inner surface 10 of plate 2 and inner surface 16 of plate 3 both bear frictionally upon the opposite surfaces of the large arm-wing 13 and in this manner prevent any accidental uplift or upswing of the locking arm 12 about its pivot 11, to assure the constant lateral as well as longitudinal interlocking of the holding plates 2, 3 to each other. During the utilization of the knife, the furrier's fingers exert opposite pressure upon the exteriors of the cooperating holder plates 2, 3, and in this manner incidentally apply positive pressure upon the opposite surfaces of the wing 13, through flexibility of plates 2, 3, whereby the locking arm 12 is positively maintained in operative condition during all working operations to assure secure retention of the cutting blade and the entire knife.

According to the modification shown in Figs. 7, 8, 9, the locking arm 12 is made of two metallic pieces 17, 18, the former being channel-shaped and providing the clamping portions 14a, 15a for the plates 2, 3, and the latter constituting the frictionally pressed interior wing 13a, which projects into the piece 17 between portions 14a, 15a and is riveted thereto at 19, the said wing being in turn pivotally joined at 11 to the plate 2.

Variations may be resorted to within the scope of the invention.

Having thus described my invention, I claim:—

1. A furrier's knife having the combination with a pair of separable plates adapted to hold a cutting blade between them of means for locking said plates to each other for retention of the blade including an arm hinged to one of said plates having a wing disposed between and in frictional contact with the inner surfaces of said plates, said arm having a clamp for engaging the exterior side of one of said plates and a clamp for engaging the exterior side of the other of said plates, and said plates when operatively held by the user exerting pressure upon the opposite surfaces of said wing.
2. A furrier's knife having the combination

with a pair of separable plates adapted to hold a cutting blade between them, of means for locking said plates to each other for retention of the blade including an arm hinged to one of said plates having a wing disposed between and in frictional contact with the inner surfaces of said plates, said arm having a clamp for engaging the exterior side of one of said plates and a clamp for engaging the exterior side of the other of said plates, said plates when operatively held by the user exerting pressure upon the opposite surfaces of said wing, and said arm with both of said clamps and said wing being made of a unitary integral piece of material.

EDWARD A. SCHMIDT.
